UNITED STATES PATENT OFFICE.

JOSEPH H. BRUCE, OF CHICAGO, ILLINOIS.

RAILWAY-CAR.

SPECIFICATION forming part of Letters Patent No. 760,847, dated May 24, 1904.

Application filed September 14, 1903. Serial No. 173,074. (No model.)

To all whom it may concern:

Be it known that I, JOSEPH H. BRUCE, a citizen of the United States of America, and a resident of Chicago, Cook county, Illinois, have 5 invented certain new and useful Improvements in Railway-Cars, of which the following is a specification.

This invention relates to certain improvements in railway-cars, and particularly in refrigerator-cars, such as are designed for the transportation of perishable freight; and the object of the invention is to provide a car of this general character of a simple and inexpensive nature and of a strong and durable 15 construction which shall be provided with refrigerating means of an improved and simplified nature by the employment of which an economy is effected in the consumption of ice and, further, by means of which an important advantage is attained in that the location of the ice-receptacles is such that the space within the car for the effective holding 20 of freight is not abridged by reason of said ice-receptacles, as in the case of refrigerator-cars as ordinarily constructed.

The invention consists in certain novel features of the construction, combination, and arrangement of the several parts of the improved refrigerator-car whereby certain important advantages are attained and the devices are made simpler, cheaper, and otherwise better adapted and more convenient for use, all as will be hereinafter fully set forth.

The novel features of the invention will be 35 carefully defined in the claims.

In the accompanying drawings, which serve to illustrate my invention, Figure 1 is a side elevation showing a car constructed according to my invention; and Fig. 2 is a sectional plan 40 view of the same, the plane of the section at the left-hand end of the figure being located just above the floor of the car, while at the right-hand end of the figure a portion of the floor is broken away to show certain parts of the car beneath the same and which will be hereinafter referred to. Fig. 3 is a partial view showing in vertical longitudinal section one end portion of a refrigerator-car embodying my improvements, and Fig. 4 is a trans- 45 verse vertical section taken through the cen-

tral part of the car and showing certain features of construction to be hereinafter referred to.

In the views, 1 1 indicate the car-trucks, and 2 indicates the platform, which will be 55 preferably constructed in such a manner as to be adapted to receive upon it a detachable body portion 9, although I do not desire to be understood as limiting myself to this peculiar construction exclusively, since it will 60 be evident that, if desired, the car-body may be fixedly held upon the platform. Where the body is detachably held upon the platform, however, it is evident that the improved car is given a much wider range of use, since 65 the removal of the body permits of using the car as a platform or gondola car, and when desired one style of body may be replaced by another style, so as to permit of readily converting the car from a refrigerator to a cattle 70 car or other variety of inclosed or box car.

The car-platform 2, as herein shown, is provided with a metal strip or band 3, extended around it, longitudinal sills 4 4 being extended along the opposite side portions of said band 75 or strip and transverse beams 6 6 being extended inside said strip 3 along the ends of the platform, while a central sill 4^a is extended lengthwise of the platform midway between the side sills 4 4. The sills 4 4 and beams 6 80 6 are cut out, as shown at 7 7, at suitable points to receive downwardly-extended parts of the car-body 9, which downwardly-extended parts by their engagement in said openings 7 7 serve for holding the car-body detachably 85 in position upon the platform. Over the platform constructed as above described is extended a floor 5, covering certain portions of the platform only, as will be hereinafter explained.

To the platform 2 are connected two metallic tanks 10 and 11, which are extended lengthwise in the spaces at opposite sides of the central sill 4^a and between the same and the side sills 4 4, and one of the said tanks, as seen at 95 10, is formed with a closed top, over which the floor 5 of the platform is extended, the said tank 10 being designed to contain liquid freight in addition to such freight as may be stored in the ordinary way within the body 9 100

of the car. The tanks 10 and 11 are separated by a space extended longitudinally beneath the central part of the car-platform, which space is adapted to receive the various 5 air-brake and other appliances, (not shown,) which are ordinarily present beneath the platform. The other tank, 11, is formed with a removable top or cover, to receive which the floor 5 of the car-platform 2 is cut out, as 10 seen in Figs. 2 and 4, the said removable cover of the tank 11 being made flush with said floor 5.

Each of the tanks 10 and 11 is formed at opposite ends with shallow portions 12 12, 15 extended above the car-trucks and having bottoms which are inclined slightly downward toward the central part of each tank, the said central portion of each tank 10 and 11 being made with an enlarged and downwardly-extended portion 13, depending in the space 20 between the car-trucks, as shown in Fig. 1. Near the ends of each tank are arranged vents 14, provided with cocks and adapted for the discharge of contents therefrom, and at one 25 end of the central enlarged part of each tank is arranged a similar valved vent or outlet 15, designed for a similar purpose.

The open-topped tank 11 is designed to receive a charge of ice, by means of which the 30 freight contained within the car-body 9 may be sufficiently cooled to prevent deterioration in transit, the ice being packed in cake form within the said tank. For the charging of the tank 11 with ice the cover thereof will 35 require to be removed, and to facilitate the removal thereof I preferably make said cover in a series of sections 17 17 end to end and supported upon ledges extended along the sides and ends of the tank and upon cross-braces 16, extended transversely across the 40 tank at suitable intervals and adapted to support the adjacent ends of the sections 17 of the cover.

The cover-sections 17 17 are provided with 45 openings or perforations 18 for the circulation of air from the body 9 of the car, so that the air within the car-body will be properly chilled to preserve the perishable freight contained within it, and for a similar purpose I 50 provide pipes or flues 19, extended within the hollow walls of the car-body at suitable intervals, the lower ends of said pipes or flues 19 being in communication when the body is in place on the car-platform with short pipes 55 or flues carried in the platform and communicating with the interior of the tank 11 beneath the floor 5 of the car-platform, while the upper ends of the pipes or flues are carried to a suitable elevation above the floor 5 60 and are passed, as indicated in dotted lines in Fig. 4, through the interior wall or lining of the car-body 9, so as to be adapted for communication with the interior thereof. Any required number of the pipes or flues 19 may 65 be employed, and although in Fig. 2 I have

only indicated the positions of two such pipes or flues it will usually be desirable to employ a greater number. The pipes or flues serve to promote circulation within the car, so that the air therein is more effectively chilled.

The ice-tank 11 will preferably be formed with double walls, as indicated in Figs. 3 and 4, and the upper part of the inner wall will be arranged slightly below the upper edge of the outer wall, which latter is flush with the car-floor, so that such upper part of the inner wall forms the ledge upon which the edges of the cover-sections of the ice-tank are rested, and the slope or inclination of the ends thereof will serve to drain from the end portions 12 12 any water resulting from the melting of the ice, which water will flow down the inclined bottom of each end portion 12 and will pass into the central deeper portion 13, whence it may be drawn off at the vent or outlet 15. 85 Should water collect within the end portions 12, it may be drawn off in a similar way at the vents or outlets 14 14. To protect the walls of the ice-tank 11 against damage from the falling of ice upon the bottom thereof, a protective grating or ice-rack 13^a, of wood or the like, as seen in Figs. 3 and 4, may be extended upon the bottom thereto. The ice-tank 11 will also be preferably provided with a door in the outer side of its enlarged central portion 13, as shown at 20 in Fig. 1, through which door cakes of ice may be inserted to replenish the supply within the tank when the same becomes exhausted on long runs. By this means it is not required to open 100 the car to replenish the ice-supply, and consequent damage to the perishable contents is avoided.

In the use of the improved car constructed according to my invention the tank 11 will 105 be packed with ice either prior to the loading of the car or during such loading, the cover-sections 17 being applied over the ice as the tank is filled, and after the doors of the car are closed the circulation of the contained air 110 through the pipes or flues 19 19 and perforations 18 18 will serve to chill the air by bringing it in contact with the ice within the ice-tank, so as to preserve the contents of the car-body 9 during transit.

The arrangement of the ice-tank 11 beneath the floor of the car permits said tank to be filled with much less labor and in less time than is required when the ice must first be lifted above the roof of the car for insertion 120 in ice-receptacles extended down from the roof in the ordinary way, and, moreover, the improved arrangement of the ice-tank below the car-floor does not in any way encroach upon the space of the car-body available for 125 the storage of freight, so that the capacity of the car is greatly increased over refrigerator-cars as ordinarily constructed. It will also be seen that since the car-body is removable from the platform it may be readily replaced 130

with another style of body, so as to adapt it for other uses when not required for use as a refrigerator-car, and since refrigerator-cars are generally run upon the return trip empty 5 the employment of the tanks 10 and 11 below the car-platform serves to render the car capable of carrying upon such return trips loads of oil or other liquid freight without danger of damaging the body 9 or rendering 10 the same unfit for refrigerating purposes.

From the above description it will be seen that the improved railway-car constructed according to my invention is of an extremely simple and inexpensive nature and is especially well adapted for use for refrigerating and other purposes, and it will also be obvious from the above description that the improved car is capable of considerable modification without material departure from the 15 principles and spirit of the invention, and for this reason I do not wish to be understood as limiting myself to the precise form and arrangement of the several parts of the device as herein set forth in carrying out my invention in practice. 20

Having thus described my invention, what I claim, and desire to secure by Letters Patent, is—

1. A railway-car comprising a platform, a 30 car-body arranged above the platform and removably held thereon, an open-topped ice-tank extended in the platform beneath the car-body and adapted to receive a charge of ice, a removable perforated cover extended over the 35 open top of the ice-tank, and means for promoting a circulation of air from the upper part of the car-body to the ice-tank and comprising flues extended in the walls of said car-body with upper ends adapted for communication with the interior of the car-body at the 40

upper part of the walls and other flues extended in the platform in communication with the interior of the ice-tank and also adapted for communication with the lower ends of the flues in the side walls of the car-body when 45 said car-body is arranged upon the platform.

2. A railway-car comprising a platform, a car-body above the platform, an open-topped ice-tank extended lengthwise in the platform, trucks at the ends of the platform whereon 50 the car is supported, said tank having shallow portions extended over the trucks and having a deeper central portion extended down in the space between the trucks, and a cover formed of sections each of which is perforated, the 55 several sections of said cover being each supported removably over the open top of the ice-tank, and said cover-sections being adapted, when removed, to afford access to the ice-tank throughout the entire length of the same. 60

3. A railway-car comprising a platform, a car-body above the platform, an open-topped ice-tank extended lengthwise in the platform below the body and having double walls, the inner wall of said tank being of less height 65 than the outer wall of the tank and having its upper edge portion arranged as a ledge surrounding the upper part of the tank and a cover for said tank, said cover being formed of perforated sections arranged end to end 70 and removably extended across the top of the ice-tank with edge portions rested on the ledge formed of the inner wall of said tank.

Signed at Chicago, Illinois, this 13th day of August, 1903.
